UNITED STATES PATENT OFFICE.

CHARLES W. WADSWORTH, OF MERRICK, NEW YORK, ASSIGNOR TO T. FRED MOORE, OF NEW YORK, N. Y.

DISPLAY DEVICE.

1,390,737.

Specification of Letters Patent. Patented Sept. 13, 1921.

Application filed November 17, 1920. Serial No. 424,740.

To all whom it may concern:

Be it known that I, CHARLES W. WADSWORTH, a citizen of the United States, residing at Merrick, in the county of Nassau and State of New York, have invented certain new and useful Improvements in Display Devices, fully described and represented in the following specification and the accompanying drawing, forming a part of the same.

This invention relates to display devices, and has for an object to provide an attachment for flexible posters or like articles which serves to hold the poster flat for display purposes while permitting the poster to be rolled into a small package for ease in transportation.

According to my invention, a poster or similar article is mounted or printed on flexible material such as cloth or paper. Two stiff or rigid members are attached to opposite edges of the poster, and to one of these edge members is permanently pivoted a folding thrust piece. The thrust piece is adapted to lie against the edge member to which it is pivoted, when it is folded, and to engage the other edge member and exert a thrust between the edge members when it is extended.

The invention will be fully understood from a detailed description of the embodiment of it illustrated in the accompanying drawings, in which:

Figure 1 is an edge elevation of the device with the poster stretched flat for display:

Fig. 2 is a rear elevation of the device with the poster stretched flat, indicating in dotted lines a position which the thrust member assumes as it is being folded; and

Fig. 3 is a top view showing the thrust member folded against the edge member to which it is pivoted preparatory to rolling up the poster for transportation.

The poster 10 comprises a sheet of flexible material such as cloth or paper on one side of which display matter is printed on otherwise displayed. To the rear side of opposite ends of the sheet are attached parallel rigid edge members or strips 11, 12.

The extensible thrust piece comprises two thrust members 14 and 15 which may conveniently be made of straight flat strips of wood. The outer end of the upper thrust

member 14 is pivotally attached to the back of the edge member 11 at the middle point of the edge member by means of a rivet 16 which extends perpendicularly to the edge member 11. The inner ends of the two thrust members 14, 15 are overlapped and pivotally attached together by a rivet 17 which is parallel to the rivet 16. The outer end of the thrust member 15 is provided with means for detachably engaging the edge member 12. In the form shown such means consists of a pin 18 projecting from the end of the thrust member and adapted to enter a socket 19 in the inner edge of the edge member 12 at its middle point.

The combined length of the thrust members 14, 15 is, of course, necessarily substantially equal to the length of the poster 10. The lengths of the two thrust members 14 and 15 are so proportioned that neither of them projects objectionably beyond the sides of the poster when in the folded position shown in Fig. 3. When possible, the length of the thrust member 14 is not greater than one-half the width of the poster, and the length of the thrust member 15 is made not greater than the width of the poster so that neither of the thrust members projects beyond the sides of the poster when the thrust piece is folded. If, however, the poster is more than one and a half times as long as it is wide, it is not possible to arrange the thrust member 14, 15 so that they fold within the width of the poster. In this case the length of the thrust member 14 is made one-third the length of the poster and the other thrust member is made two-thirds of this length so that the projection of the thrust piece when folded is as small as possible.

The use of the device described is as follows:—When the poster is to be displayed, it is unrolled and the thrust members 14 and 15 are moved about their pivots until they extend nearly straight across the back of the poster. The outer end of the thrust member 15 is then inserted in the socket 19 in the edge member 12 and the pivot 17 of the thrust piece is moved sidewise until the members are extended in a straight line as shown in Figs. 1 and 2. This movement results in causing an outward thrust on the edge members 11 and 12, drawing the poster flat. The friction between the overlapping ends of the thrust members 14 and 15

tends to prevent relative angular movement of these members and thus to prevent the accidental displacement of the pivot point 17 when the poster is extended as described.

5 It should be noted that owing to the fact that both the pivots 16 and 17 are perpendicular to the edge piece 11 and consequently to the surface of the poster 10 when extended, the movement of the thrust piece 10 in folding is in a plane parallel to the poster so that the inner ends of the thrust pieces cannot move toward the poster and tear or injure it as the attachment is being folded.

When it is desired to transport the poster, 15 the pivot 17 is moved sidewise disengaging the pin 18 from the socket 19. The thrust members 14 and 15 are then swung about their pivots until they lie flat against the back of the edge member 11, as shown in 20 Fig. 3. The poster 10 is then rolled closely about the edge member 11 and the folded thrust piece which have been compactly folded together, so that the poster and the attachment form a small package which may 25 easily be transported.

Various changes may be made in the embodiment shown without departing from my invention. Thus other means than the friction between the overlapping ends of the 30 thrust members may be used to retain the thrust piece in extended position. Other forms of connection between the thrust member 15 and the edge piece 12 may be used. I shall not, however, attempt to set 35 forth all such changes.

What is claimed is:

1. The combination with a flexible poster, 40 of edge members attached to opposite edges of the poster, and a foldable thrust piece, comprising a plurality of thrust members pivotally attached together, said thrust piece being permanently pivoted at one of its ends to one of the edge members and having its other end adapted to engage the other of said 45 edge members so as to exert an outward thrust on said edge members when extended and to lie against the edge member to which it is pivoted when folded.

2. The combination with a flexible poster, 50 of edge members attached to opposite edges of said poster, and a thrust piece comprising a member having one of its ends attached to one of said edge members by a pivot which permits it to swing from a position in line 55 with said edge member to a position at right angles to said edge member, and a member having one of its ends attached to said first mentioned thrust member by means of a pivot which permits it to swing through an 60 angle of 180° relatively to said first mentioned thrust member and having its other end adapted detachably to engage the other of said edge members, said two pivots being

parallel and perpendicular to the edge member to which the thrust piece is pivoted. 65

3. The combination with a flexible poster, 70 of edge members attached to opposite edges of said poster, and a thrust piece comprising a member pivoted at one of its ends to one of said edge members and a member pivoted at one of its ends to said first-mentioned thrust member and having its other end adapted detachably to engage said other edge member, said thrust piece being adapted to exert an outward thrust on said edge members 75 when its thrust members are extended in a straight line and to lie against the one of said edge members to which it is pivoted when its thrust members are folded together.

4. The combination with a flexible poster, 80 of edge pieces attached to opposite edges of said poster, and a thrust piece comprising a thrust member pivoted at its outer end to one of said edge members and not materially greater in length than the distance from 85 the pivot point to one end of said edge member, and a thrust member pivoted at its inner end to the inner end of said first-mentioned thrust member and not materially greater in length than said edge members, so that when 90 said thrust piece is folded upon said edge member it does not project materially beyond the ends thereof, said thrust piece having its free end adapted to engage said other edge member and being adapted to exert an 95 outward thrust upon said edge members when said thrust members are extended in a straight line.

5. The combination with a flexible poster, 100 of edge members attached to opposite ends of said poster, and a thrust piece comprising a thrust member having its outer end pivotally attached to one of said edge pieces at its middle point and not materially greater in length than one-half of the width of said 105 poster and a thrust member having its inner end pivoted to the inner end of said first mentioned thrust member and its outer end adapted to engage said other edge member and not materially greater in length than 110 the width of said poster, so that when said thrust piece is folded it does not extend materially beyond the sides of the poster, the combined length of said thrust members being substantially equal to the length of the 115 poster so that when they are extended in a straight line they exert an outward thrust upon said edge members to draw the poster flat.

In testimony whereof I have hereunto set 120 my hand in the presence of two subscribing witnesses.

CHARLES W. WADSWORTH.
